E. BALOD.
COMBINATION SAW.
APPLICATION FILED JAN. 25, 1921.

Patented July 26, 1921.

UNITED STATES PATENT OFFICE.

EDWARD BALOD, OF NEW YORK, N. Y.

COMBINATION-SAW.

1,385,855.

Specification of Letters Patent. Patented July 26, 1921.

Application filed January 25, 1921. Serial No. 439,722.

To all whom it may concern:

Be it known that I, EDWARD BALOD, a citizen of Russia, having declared my intention to become a citizen of the United States, residing at New York city, in the county of New York and State of New York, have invented certain new and useful Improvements in Combination-Saws, of which the following is a specification.

10 This invention has relation to carpenter tools with particular reference to wood saws, and has for an object to provide a woodsaw in which there is embodied a number of features which will permit the performance 15 of functions other than the mere sawing of wood, such as the determination of right angles and other angles as well as the measurement of linear dimensions, etc.

Another object of the invention is to provide a combination saw consisting of a saw-blade of conventional type having described upon one edge a scale divided into inches or other units of measurement and having a handle formed in such a manner that it may 25 be engaged against the edge of the material to be cut to form a guide, the graduated edge of the blade being located at right angles to said guide serving as a rule whereby indicating marks may be made upon the material 30 to facilitate the sawing thereof.

In addition to the foregoing this invention comprehends improvements in the details of construction and arrangement of parts to be hereinafter described and particularly 35 set forth in the appended claims.

In the accompanying drawings, in which similar and corresponding parts are designated by the same characters of reference throughout the several views in which they 40 appear,—

Figure 1 is a view in side elevation of a tool constructed in accordance with my invention;

Fig. 2 is an edge view thereof; and

45 Fig. 3 is a view illustrating the manner in which my improved tool can be moved upon the work when selecting an angle at which said work is to be cut.

With reference to the drawings, 10 indicates a blade having the general appearance of a conventional saw blade of the cross-cut saw type, and 11 indicates a handle formed in a conventional manner with the exception that at the point of attachment thereof 50 of with the blade the handle is provided with an extension 12 projecting a short dis-

tance beyond the back edge of the blade. Also, the material of the handle to which the blade is attached is provided with a relatively broad surface 13 adapted to bear 60 against the edge of a plank or the like to thus form a guide whereby the saw may be moved along, the back edge 14 of the blade being exactly at right angles to the edge of the plank, etc., against which the guide 65 13 bears. The surface of the blade adjacent the back edge 14 is graduated beneath its other units of measurements as indicated at 15 to form a scale for measuring linear dimensions. Also, I prefer to inscribe 70 upon the face of the saw a line indicated at 16 which extends from the corner of the handle or the guide face across the blade at an angle of 45 degrees for example, relative to the rear edge of the saw. A notch 17 is 75 provided in the rear or back edge of the saw blade, one face or edge 17' of said notch being coincident with the line 16, and the other face of the said notch lying at an angle, preferably a right angle, to said line 80 16. This construction facilitates the positioning of the saw with the edge 17' of the notch in alignment with the edge of the plank.

In practice the edge or portion 17' of the 85 notch can be readily positioned on the edge of the plank and in the use of the saw should the line 16 become defaced or blurred, the notch will serve to locate the angle desired.

When the blade is placed upon a plank or the like the surface or guide 13 bears against the edge thereof, and the back or rear edge of the blade forms a rule along which a pencil or marker may be moved to inscribe a line upon the plank at right angles to the 95 edge thereof. In using the notches and extending lines as well as the graduations, the lower corner of the handle or guide face becomes a fulcrum against the edge of the plank and the saw blade is moved until the 100 edge or the face 17' of the notch is aligned with the edge of the plank. A marker is then run along the back edge 14 of the blade passing over the notches and the line inscribed upon the plank will be exactly 105 45 degrees relative to either edge thereof. The marker may be inserted in the notch 17 to inscribe an indication upon the object to be measured.

Fig. 3 illustrates the manner in which the 100 tool is used when marking the plank or other work. A series of angles 18 is shown

on the saw blade, the angle of 45 degrees being alined with the edge of the plank when the saw is swung about point 19. In a similar manner each of the lines or notches indicating the respective angles can be brought into register with or moved co-incident to the edge of the plank as will be understood.

Other uses and advantages will readily occur to those familiar with the art to which this invention appertains. It will however be seen that I provide a novel tool which is capable of performance of the ordinary functions of sawing and which at the same time may be utilized as a square, or to get any desired angle, thus eliminating these tools which are ordinarily included in the equipment of a carpenter and which are more or less heavy and bulky.

While I have illustrated and described my invention with some degree of particularity, I realized that in practice various alterations therein may be made. I therefore reserve the right and privilege of changing the form of the details of construction or otherwise altering the arrangement of the correlated parts without departing from the spirit of the invention or the scope of the appended claims.

Having thus described my invention what I claim is new and desire to secure by United States Letters Patent is:—

1. A tool involving a saw blade, a handle affixed thereto and provided with a lateral

surface at right angles to the rear edge of the blade, and a line upon a face of the blade forming one face of an angle extending from a point on the rear edge of the blade to the lower corner of the handle.

2. A tool involving a saw blade, a handle affixed thereto having a lateral surface arranged at an angle to an edge of the blade, a series of graduations provided on said edge, and a notch in said edge with one face thereof coincident with a line drawn from said face through a corner of the aforesaid handle.

3. A tool involving a saw blade, a handle affixed thereto and provided with a lateral surface at an angle to the rear of the edge of the blade, graduations on said edge, and other means associated with the rear edge of the blade arranged to form a series of angles, a face of each angle extending from a point on the rear edge of the blade to a corner on the handle about which the saw may be moved.

4. A tool involving a saw blade having a handle, a guide having a straight face adjacent said handle and arranged at an angle to the rear edge of the blade, graduations on said edge, and other means associated with said rear edge of the blade to form an angle between the rear edge of said blade and the lower corner of the aforesaid guide about which latter the saw may be moved.

In testimony whereof I affix my signature.
EDWARD BALOD.
